DISTILLING APPARATUS FOR RECLAIMING
USED LUBRICATING OILS

Francis E. Symons and Frank M. Cowgill,
Columbus, Ohio, assignors to Ralston Steel Car
Company, Columbus, Ohio, a corporation of
Ohio

Application March 25, 1932, Serial No. 601,168

13 Claims. (Cl. 196—104)

This invention relates to improvements in apparatus for reclaiming used lubricating oils, and has for its primary object the provision of an improved still for effecting through distillation the removal of low boiling liquids or compounds from a given body of lubricating oil whereby to restore the viscosity and other lubricating properties of the oil to permit of its reuse in the same manner as a new lubricating oil.

It is another object of the invention to provide a distilling apparatus of the character set forth wherein provision is made for introducing hydrocarbon gas into the oil undergoing distillation in such a manner as to facilitate the distilling operation and to effect, in an efficient and effective manner, the removal of the undesired low boiling constituents or diluents which are normally contained in the oil undergoing such distillation.

With these and other objects in view, which will appear as the description proceeds, the invention consists in the novel features of construction, combination of elements and arrangements of parts hereinafter fully described and pointed out in the appended claims.

In the accompanying drawings:

Fig. 1 is a side elevation of the distilling apparatus comprising the present invention;

Fig. 2 is an end elevation thereof;

Fig. 3 is a transverse vertical sectional view taken through the still on the line 3—3 of Fig. 1;

Fig. 4 is a horizontal sectional view taken through the inlet header of the still;

Fig. 5 is a detail vertical sectional view taken through the still on the plane indicated by the line 5—5 of Fig. 4 and disclosing more particularly the transverse configuration of the header and the means employed for mounting the same in connection with the lower portion of the still;

Fig. 6 is a detail longitudinal sectional view taken on the line 6—6 of Fig. 4 disclosing the gas inlet pipes arranged in the bottom of the still;

Fig. 7 is a detail view taken on the line 7—7 of Fig. 6 disclosing the means for retaining the positions of the free ends of the gas inlet pipes of the still;

Fig. 8 is a transverse vertical sectional view taken on the line 8—8 of Fig. 2 and disclosing more particularly the gas expansion chamber arranged above the vapor condenser of the apparatus;

Fig. 9 is a detail longitudinal sectional view taken through the gas preheater and the vapor outlet of the still;

Fig. 10 is a transverse vertical sectional view on the line 10—10 of Fig. 9;

Fig. 11 is a similar view on the line 11—11 of Fig. 9.

The distilling apparatus comprising the present invention has been particularly described for use in the rejuvenation of used lubricating oils. It is known that after lubricating oils have been employed in, for example, internal combustion engines, the oils lose their viscosity by having admixed therewith unburned low boiling motor fuels, carbon, water and other incidental impurities, and it is the purpose of the present invention to treat such used lubricating oils whereby to remove therefrom the undesirable compounds, to restore the viscosity of the oil, correct its color and generally to render it entirely suitable for reuse as an improved lubricant. To accomplish this end, a given body of used lubricating oil is first subjected to treatment in an agitated state with sulphuric acid, whereby to liberate and precipitate free carbon and other solids contained in the used oil.

Following the removal of the acid sludge produced by this treatment, the oil is then washed with a neutralizing alkali and is subjected to distillation preferably in the presence of hydrocarbon gas, steam, or other inert gaseous fluid. By this step of distillation, the low boiling compounds present in the oils are removed as vapors, particularly compounds such as water, gasoline and in certain instances kerosene, whereby to leave in the still a residue composed of viscous liquid hydrocarbons constituting lubricating oil fractions. These latter fractions are then withdrawn from the still and have admixed therewith fuller's earth or activated clay and this oil-clay mixture is advanced under pressure to a filter press for the purpose of removing from the oils those compounds which tend to discolor the same, whereby the expressed oils will possess all of the attributes of freshly made high grade lubricating oils and are capable of being placed to the same services.

The present invention deals more particularly with the apparatus employed for effecting the distillation of the acid treated oils for the purpose of removing the low boiling diluent, the process as a whole being set forth in our co-pending application, Serial No. 600,197, filing date March 22, 1932, and the details of our improved filter press, Serial No. 599,470 filing date March 17, 1932.

As shown in Fig. 1, our improved still comprises a setting or furnace structure 1 of suitable heat retaining walls and in this instance the interior of the setting is provided with a grate structure

2 adapted for the burning of solid fuel. It will be understood, however, that other heat developing appliances, such as oil or gas burners, may be used if desired for securing necessary distillation temperatures. The distillation zone of the still comprises a metallic structure formed to include a bottom wall 3 arranged over the grate 2 and disposed in a substantially horizontal plane, the said wall 3 being supported by the upper portion of the burner setting. Secured to and arising from the wall 3 are inner and outer spaced metallic shells 4 and 5 respectively, a structural spacing member 6 being interposed between the inner and outer shell to maintain the latter in rigidly assembled yet spaced relationship. If desired, the outer shell may be provided with suitable heat insulating material (not shown) to reduce heat losses, although the spacing of the shells is of material assistance in this respect. 10 The upper portion of the inner shell 4 is provided with a vapor dome 7 and extending downwardly through this dome and terminating immediately above the bottom wall 3 is an oil inlet pipe 8. By means of this pipe, acid treated oil is introduced into the shell 4 to a desired amount. After which, the distillation proceeds on the batch principle, as is common in shell stills. The operation of the furnace structure 1 is carried out in such a manner as to heat the oil in the distillation zone to requisite temperatures necessary to vaporize the undesired lower boiling liquids, such, for example, as water, gasoline or kerosene which may be contained therein. The vapors, without any substantial cracking of the oil pass upwardly 20 into the dome 7 and are removed as formed from the still by way of the vapor outlet 9 communicating with said dome. Usually the distillation is carried on at ordinary or atmospheric pressures, although it is within the range of the invention to employ sub-atmospheric pressures or in certain instances superatmospheric pressures. With the employment of sub-atmospheric pressures in the still lower temperatures of distillation may obtain thus removing the possibility of overheating or 30 cracking the oil, which would interfere with its value as a lubricant.

To facilitate the distillation process, the present invention provides for the introduction of a gaseous fluid into the oil disposed within the shell 4 whereby to promote heat transfer and to assist in carrying on the undesired low boiling compounds. A preferred structure for accomplishing this purpose consists in the provision of a plurality of horizontally disposed pipes 10 which extend transversely over the bottom wall 3. These pipes are provided with spaced perforations 11 so that a gas supplied to the pipes from a common header 12 will issue from the perforations and pass upwardly through the body of oil contained in the still. Natural or artificially produced hydrocarbon gas may be used for this purpose and in certain instances superheated steam.

As shown in Fig. 5, the still walls, adjacent to the header 12, are provided with a longitudinally extending opening 13 and a closure plate 14 is detachably connected with the outer walls of the still through the use of positioning studs 15. A gasket 16 is preferably interposed between the plate 14 and the wall of the still. Also arranged to engage with the plate 14 is an outer gasket 18, the latter being interposed between the outer surfaces of the plate 14 and the inner surfaces of the header 12. This header preferably provides a unitary casting having its upper portion

provided with hinged ears 19, which register with corresponding ears formed in connection with hinged brackets 20, which are secured to the outer walls of the still. The header has cast therein a longitudinally extending horizontally disposed passage 21, which is provided with a plurality of laterally disposed communicating slots 22, which register with the inlet openings of each of the pipes 10. Gas is admitted into the passage 21 by way of a gas supply pipe 23 which, adjacent to the header, is provided with a header coupling 24. By this arrangement gas may flow lengthwise of the passage 21 and thence into each of the laterally disposed slots 22, entering the pipes 10 and issuing from said pipes through the perforations 11 formed therein whereby to pass through the body of oil contained in the still, agitating the oil and liberating freely the low boiling compounds which the oil contains. The ends of the pipe 10 opposite to the header 12 are provided with caps 25 which are frictionally held in engagement with the upper surface of the bottom wall 3 by the employment of resilient strips 26, which serve to confine the free ends of said pipes and prevent undue movement on the part thereof. The lower portions of the header 12 are provided with slotted lugs 27, which receive the shanks of pivotally movable bolts 28, the latter being pivotally carried as at 29 by brackets secured to the walls of the furnace structure 1. The bolts 28 have their outer ends threaded for the reception of binding nuts 30, by means of which the header may be retained in firm frictional engagement with the outer gasket 18 and also the plate 14 may be similarly retained in fluid tight engagement with the inner gasket 16 and the wall of the still adjacent to the opening 13. If it is desired to remove the pipes 10 for cleaning and other purposes, the nut 30 may be loosened, permitting of the dropping of the bolt 28. Then by disconnecting the pipe, such as the gas supply pipe 23 entering the header, the said header may be swung outwardly and upwardly about the pintles of the ears 19 and the pipes may be withdrawn by applying outwardly directed forces on the plate 14 in connection with which the pipes are carried. This provides free access to the longitudinally extending opening 13 in the bottom of the still permitting of the removal of accumulated deposits or residues from the bottom of the still whenever required.

After distillation has been carried on for the required period of time to remove the volatiles from the oils and to reduce the latter to the desired degree of viscosity, the volatile freed oils may be removed from the bottom of the still by way of outlet ports 31 formed in the plate 14 and the inner wall of the header 12. Normally these ports are closed by means of needle valves 32 which are provided with threaded bodies 33 receivable within correspondingly threaded seats provided in connection with the ports 31. The valves each include outwardly and horizontally extending stems 34, which are positioned within packed glands 35 carried in connection with the outer wall of the header. By rotating the stems 34, the needle valves may be removed from engagement with their seats providing for free oil flow through the ports 31 and thence into an oil duct 36 formed longitudinally within the header 12. This duct is connected with an oil outlet pipe 37 leading to a suitable and convenient point of discharge.

To supply the pipes 10 with the hydrocarbon gases, use is made of a supply line 38 shown par-

ticularly in Fig. 2. This line is provided with a check valve 39 and gas from any suitable source of supply, such as a city gas main, is permitted to flow through the line 38, past the control valve 40 and thence upwardly into an expansion chamber 41. In this chamber any water contained in the gas is trapped and removed from the chamber by way of the drain line 42, the latter being valved as at 43. Mounted on the top of the chamber 41 is a compressor or pump 44 which in this instance is driven by an electric motor 45. The discharge side of the compressor or pump is connected with a pipe line 46 provided with a valved by-pass 47 returning to the expansion chamber 41, the said by-pass serving to maintain desired pressure on the gas discharge through the line 46 and may be said to relieve automatically excessive pressures. The pipe line 46, as shown especially in Fig. 9, leads to a preheater 48 which, in the present instance, comprises a drum arranged to surround the vapor outlet 9 of the dome 7. The gases entering the preheater from the pipe line 46 are caused, by means of a baffle 49, to pass longitudinally through the preheater in contact with the pipe line 50 leading from the outlet 9. This results in increasing the temperature of the gas and to a certain extent cooling the vapors, thereby promoting the heat economy of the system. The gases discharged from the preheater travel by way of the pipe line 51 to the vertically extending pipe 23 which enters or communicates with the gas supply passage of the header 12. The pipe line 51 and the supply pipe 23 may be provided with an exterior coating of heat insulating material to minimize heat loss. Likewise the header itself may be similarly coated.

The gases and vapors of low boiling liquids are passed through the pipe line 50 to a cooling coil 40 and condenser 52 arranged in a casing structure 53 which is also used to effect the support to the expansion chamber 41. In the condenser 52, the temperature of the fluids discharged from the still is reduced sufficiently below the vaporizing point of such fluid as to liquefy the normally liquefiable constituents thereof. These liquids and gases pass from the condenser by way of a valved outlet 54 and are delivered to a cylindrical tank 55 arranged on one side of the casing structure, as shown in Figs. 1 and 2. The bottom of the tank is provided with a liquid draw-off line 56 and a gauge glass 57 may be provided at one side of the tank to indicate the liquid levels therein. The gases drawn off the top of the tank pass by way of a valve pipe line 58 to the expansion chamber and the inlet side of the pump or compressor 44 arranged on the top of the expansion chamber, in order that such gases may be returned to the distillation system for use therein. This feature of recycling the gases effects a very considerable economy in the operation of the system and maximum efficiency. The pipe line 58 may be also provided with a valved shunt 59 permitting of the withdrawal of gas from the system when desired.

The base of the casing structure is provided with an electric motor 60 which is used to effect the operation of a pump 61 and to the inlet side of this pump there is connected the pipe line 62 for delivering the oils to be processed to the distillation zone. Preferably, this is a lubricating oil which has been previously acid treated, as explained above. The outlet side of the pump 61 is connected with a valved pipe line 63, which leads to the oil inlet pipe 8 extending through

the dome 7. The bottom of the casing structure, below the condenser 52 is provided with a reservoir 64, and the liquid oil removed from the bottom of the still by way of the header 12, and from which low boiling compounds have been removed, is connected with the outlet pipe 37, in order that such lubricating oils of desired viscosity may be transferred from the still to the reservoir 64 for cooling and storage. The outlet of the reservoir is connected with the inlet side of a pump 65, the operation of which is effected through the motor 60. By means of the pump 65, the cooled lubricating oil fraction which, while possessing the desired viscosity and freedom from low boiling diluent, yet ordinarily possesses a darkened and undesirable color, and the pump 65 is used to transfer this oil to a filter press, as shown in our copending Patent No. 1,903,363 whereby the oil may be treated to effect the removal of these undesired color compounds and to impart to the finished oil the desired coloration. Starting switches 66 may be mounted on the sides of the casing structure for the purpose of controlling the operation of the electric motors 45 and 60. Preferably, the bottom wall of the expansion chamber is inclined to provide for the gravity drainage of water or other liquids which may accumulate within said chamber.

In view of the foregoing, it will be seen that the present invention provides a still of particularly economical and efficient construction for use in the reclamation of used lubricating oils, although in its broader aspects, the still may be used in connection with any other desired distillation operation and we contemplate the use of our invention in any field or specific use to which it may be adapted. While the still has been disclosed in its preferred form, nevertheless it will be appreciated that its construction as herein depicted and described is subject to considerable variation and, therefore, we claim as our invention all such modifications thereof as may be said to fall within the scope of the following claims.

What is claimed is:

1. A still comprising a liquid holding shell, means for heating the shell and liquid contained therein, said shell being provided contiguous to its lower portion with a longitudinally extending opening, a header movably secured in fluid tight engagement with the walls of said shell and engaging with the portions of said shell immediately surrounding said opening, said header being provided with a longitudinally extending passage communicating with a source of gaseous fluid supply, said passage being provided with laterally extending branches, pipes arranged within said shell and communicating with said branches whereby to admit of the issuance of gaseous fluid into the liquid within the shell through apertures formed at spaced intervals in said pipes, and valve means for controlling the outflow of liquid from said shell through separate outlet passages provided in said header.

2. A still comprising a liquid holding shell, means for heating the liquids contained within said shell, said shell being provided along one side with a longitudinally extending opening, a header movably secured in fluid tight engagement with the walls of said shell immediately adjacent to said opening, said header being provided with a longitudinally extending gas inlet passageway and a spaced liquid outlet passageway, a plurality of perforated pipes positioned

in said shell and communicating with the gas inlet passageway of the header, means for removing vapors from the upper portion of the shell, and valve means for removing liquids from the lower portion of the shell through ports provided in conjunction with said header, and controlling communication between said shell and said liquid outlet passageway.

3. In a still, a liquid holding shell, means for heating liquids contained within the shell, said shell being provided with a vapor outlet in its upper portion and with a longitudinally extending liquid outlet in its lower portion, a header removably secured to said shell contiguous to said liquid outlet, clamping means cooperative with said header for normally maintaining the same in fluid tight engagement with the side walls of the shell, said header being provided with a longitudinally extending gas passageway, a plurality of perforated pipes mounted in the lower portion of said shell and communicating at one end with the gas passage provided in the header, and valve mechanism provided in connection with said header for effecting the removal of liquids from said shell.

4. In a still, a liquid holding shell provided at one side with a longitudinally extending opening, means for heating liquids contained within the shell to distillation temperatures, a movable header carried by said shell and normally closing said opening, said header being provided with spaced fluid inlet and discharge passages, means for introducing a gaseous fluid into the liquids contained within said shell through the inlet passage provided in said header, and valve means carried by said header for governing the outflow of liquid from said shell through the discharge passage provided in said header.

5. In a still, a liquid holding shell, means for heating liquids contained in said shell to distillation temperatures, vapor outlet means provided in the upper portion of said shell, a liquid outlet in the lower portion of said shell, a pivotally mounted header carried by said shell and normally serving to close said opening, and means provided in said header for introducing a gaseous fluid into the liquids contained within the shell.

6. In a still, a liquid holding shell, means for heating liquids contained in said shell to distillation temperatures, vapor outlet means provided in connection with the upper portion of said shell, a liquid outlet in the lower portion of said shell, a pivotally mounted header carried by said shell and normally serving to close said outlet, gas inlet means formed in said header for introducing a gaseous fluid into the liquids contained within the shell, and valve means for regulating the outflow of liquid from said shell through discharge passages formed in said header and spaced from the gas inlet means.

7. In an oil still, a liquid containing shell, means for heating liquids contained within the shell to distillation temperatures, a vapor outlet leading from the upper portion of said shell, means for introducing a liquid to be distilled into the lower portion of said shell, said shell being provided at one side thereof contiguous to its lower portion with a longitudinally extending liquid outlet opening, a header detachably clamped to the outer wall of said shell immediately adjacent to said opening, means for introducing a gaseous fluid into the liquid contained within said shell through passages provided in said header, and valve controlled means for re-

moving liquids from said shell through a separate set of passages provided in said header.

8. In a still, a liquid holding shell provided with a substantially flat bottom and upstanding side walls, means for heating liquids contained within said shell to distillation temperatures, said shell contiguous to the bottom thereof being provided along one side with a longitudinally extending opening, a header removably secured to the outer wall of said shell immediately contiguous to said opening and normally serving to close the latter, said header being provided with a longitudinally extending passage formed with a plurality of laterally extending branches, transversely extending perforated pipes arranged within said shell and extending transversely across the bottom thereof, said pipes being connected at one end to the header in communication with said lateral branches, means for supplying said passages with a gaseous fluid for delivery to the liquid contained within said shell through said perforated pipe, and valve means carried by said header for controlling the outflow of liquid from said shell through ports communicating with a liquid discharge passage formed in said header.

9. In a still, a liquid holding shell provided with a substantially flat bottom and upstanding side walls, means for heating the shell, said shell being provided along one side thereof contiguous to said bottom with a longitudinally extending opening, a plate arranged exteriorly of the shell to close said opening, a plurality of perforated pipes connected with said plate and extending transversely across and immediately adjacent to the bottom of said shell, a header secured in connection with said plate and the outer walls of said shell, said header being provided with a longitudinally extending passage, the said passage being provided with laterally extending branches leading to each of said pipes, means for introducing a gaseous fluid into the passage of said header for issuance from the perforations provided in said pipes into the liquid of the shell, said header being provided with a separate liquid outlet passage extending longitudinally therethrough, and a plurality of independently operable valve means for governing the opening and closing of ports establishing communication between the interior of said shell and the liquid outlet passage of the header.

10. In a still, a liquid holding shell formed to comprise a substantially flat bottom wall and spaced upstanding side walls, a vapor outlet in the upper portion of said shell, means for heating said shell and the liquids contained therein, said shell being provided contiguous to said bottom and along one side thereof with a longitudinally extending opening, a removable closure arranged exteriorly of said shell and normally serving to close said opening, means for introducing a gaseous fluid into said closure for travel through a longitudinal passage provided therein, a plurality of perforated pipes connected with said closure and communicating with said passage whereby to deliver said gaseous fluid to the liquids contained within the shell, and valve means bodily carried by said closure for controlling the outflow of liquid from said shell through spaced liquid outlet passages provided in the closure.

11. In a still, a shell formed to comprise a substantially flat horizontally disposed lower wall and upstanding vertical side walls, one of said side walls being provided adjacent to the lower portion of the shell with a longitudinally extend-

ing slot, a hinged closure carried by the exterior of said shell and normally serving to close said slot, and valve means mounted in conjunction with said closure for regulating the outflow of liquid from said shell through a passageway formed longitudinally in said closure.

12. In a still, a shell provided contiguous to its bottom with a longitudinally extending slot, a hinged closure member for said slot arranged exteriorly of the shell said closure member being provided with a discharge passage arranged to register with said slot, threaded means for maintaining said closure member in fluid sealing engagement with the side walls of said shell and, valve mechanism supported by said closure member for regulating the outflow of liquid from said

shell through the discharge passage provided in the closure member.

13. In a still, a liquid holding shell provided along one side thereof with a longitudinally extending slot, a closure member provided with fluid passages hingedly connected with one of the exterior walls of said shell, threaded means cooperative with the closure member for maintaining the latter in fluid sealing engagement with the walls of said shell immediately surrounding said slot, and valve means carried by said closure member for regulating the outflow of liquid from said shell through the passages provided in the closure member.
